UNITED STATES PATENT OFFICE.

WALTER D'ARCY RYAN, OF SCHENECTADY, NEW YORK.

HEADLIGHT.

Application filed May 13, 1925. Serial No. 29,991.

My invention relates to improvements in headlights and is particularly concerned with improvements in that type of headlight comprising a housing and a reflector pivotally mounted in said housing.

The objects of my present invention are:

First, to provide a headlight of the character described that comprises means whereby the reflector can be easily and quickly 10 tilted to any desired degree;

Second, to provide means of the character described, including means for holding the reflector in any position to which it is adjusted;

15 Third, to provide a headlight comprising means for yieldingly holding the reflector in its adjusted position; and

Finally, to provide a headlight, such as described, that is simple in construction, 20 economical to manufacture and easy to adjust.

Other objects of my invention will appear as this description progresses, reference being had to the accompanying drawings, in 25 which

Figure 1 is a side elevation of a headlight embodying one form of my invention, portions of the headlight being broken away for the purpose of better illustration;

30 Figure 2 is a front elevation of the reflector itself, showing the means for pivotally mounting it upon the housing;

Figure 3 is a plan view of the strip of metal from which the bracket shown in Figures 4, 5 and 6 is formed;

35 Figures 4, 5 and 6 are end, side and bottom details of a portion of the adjusting mechanism; and

Figures 7 and 8 are an elevation and 40 sectional view, respectively, of the nut forming a part of my improved adjusting mechanism.

Referring to the drawings, I have illustrated my invention as being embodied in a headlight comprising the housing 10, having 45 a lens 11 suitably mounted in the front end thereof. A reflector 12 is suitably mounted in the housing by means of the brackets 13 which are secured to the housing by means of screws 14 and the trunnions 15 that are 50 pivotally mounted in the brackets.

For tilting the reflector about the axis formed by the trunnions 15, and for holding it in any of its adjusted positions, I provide the bracket 16, which, as shown in Figure 3, is formed from a strip of metal having 55 the key-hole shaped slot 17 formed therein.

This strip of metal is then bent along the line *a*—*a* to produce the bracket shown in Figures 4, 5 and 6. The bracket thus formed is soldered, or otherwise secured to 60 the flange 18 of the reflector in such manner that the portion of the bracket carrying the circular portion 19 of the key-hole slot is parallel with the axis of the reflector and the circular opening 19 is located just to the 65 rear of the flange 18. A screw 20 projects through the housing and the vertically extending portion of the slot 17 in the bracket. A nut 21, having the threaded opening 22 70 formed therein, and provided at its upper end with the neck portion 23 and the head 24, is threaded upon the inner end of the screw in such manner that its neck 23 is received between the edges of the slot 17 and the head 24 rides upon the spaced portions 75 of the bracket.

Immediately adjacent the threaded opening 22, the nut is pressed outwardly, as shown at 25, to provide a substantially spherical portion for contacting with the downwardly extending portion of the bracket, so 80 as to prevent binding of the nut on the bracket, when the reflector is tilted.

A washer 26 is slidably mounted upon the screw 20 and yieldingly held against the 85 downwardly depending portion of the bracket by means of the compression spring 27 that is confined between the washer 26 and another washer 28 that rests against the inner side of the housing.

90 A cotter pin 29 projecting through the inner end of the screw tends to prevent the loss of parts that are mounted upon the screw; and the slot 30, formed in the head of the screw, provides means whereby it 95 can be rotated for the purpose of adjusting the reflector.

If it is desired to remove the reflector this can be accomplished by first detaching the trunnions 15 and then turning the screw 100 20 to bring the nut 21 to the inner end of the screw. By pressing rearwardly upon the upper side of the reflector to bring the nut 21 into registry with the circular portion 19 of the key-hole slot, and then by 105 moving the reflector downwardly relatively to the nut, the bracket can be disengaged from the screw and nut.

From the above description it will be 110 apparent that I have provided simple and efficient means for adjusting the angular positions of the reflector and that inasmuch

as this means embodies a spring, the reflector will be yieldingly held in any of its adjusted positions, thereby permitting it to move slightly under any excessive shock to 6 which it may be subjected, but under normal conditions holding it in its adjusted position.

While I have described the details of construction of the preferred embodiment of my invention, it is to be clearly understood 10 that my invention is not limited to these details, but is capable of other adaptations and modifications within the scope of the appended claims.

Having thus described my invention, what 15 I claim is:

1. A headlight comprising a housing, a reflector in said housing, trunnion means for pivotally mounting said reflector in said housing, a slotted bracket secured to said 20 reflector, a screw projecting through said housing and said bracket, a nut carried by said screw and having a portion projecting through said slotted bracket, and a spring surrounding said screw and tending to hold 25 a portion of said bracket against said nut, said bracket being bodily removable with said reflector from operative engagement with said nut.

2. A headlight comprising a housing, a 30 reflector in said housing, trunnion means

for pivotally mounting said reflector in said housing, a bracket secured to said reflector, a screw projecting through said housing and said bracket, a nut carried by said screw, a spring tending to hold a portion of said bracket against said nut, and an interlocking connection between said nut and bracket for permitting complete separation of said bracket from said screw and nut without the removal of the nut from the screw. 35

3. A headlight comprising a housing, a reflector in said housing, a rotary member extending through the wall of said housing and accessible from outside, and a connection for adjusting said reflector by rotation of said member, said connection comprising a nut threaded on said member, a bracket on said reflector abutting said nut, and resilient means tending to hold said bracket and nut in abutment, said bracket having a keyhole slot and said nut having a projection slidably retained in the narrow portion of said slot, said resilient means permitting movement of said nut to the large end of said slot to disconnect and remove 50 said reflector and bracket. 55

In witness whereof I hereunto subscribe my name this 6th day of May, 1925.

WALTER D'ARCY RYAN.
